FIG. 1

FIG. 2

Inventor

Walter A. Rowe.

By H. E. Dunlap
Attorney.

UNITED STATES PATENT OFFICE.

WALTER A. ROWE, OF TIFFIN, OHIO.

LAVATORY.

1,408,830.

Specification of Letters Patent.

Patented Mar. 7, 1922.

Application filed November 7, 1921. Serial No. 513,261.

To all whom it may concern:

Be it known that I, WALTER A. ROWE, a citizen of the United States of America, and resident of Tiffin, Seneca County, Ohio, have 5 invented certain new and useful Improvements in Lavatories, of which the following is a specification.

This invention relates broadly to lavatories, and more particularly to a novel and 10 improved form of lavatory of vitreous or ceramic material.

The chief object of the invention is to provide a lavatory in which the ordinary form of overflow, in the production of which 15 much care and skill are required, is wholly dispensed with and a substitute means for accommodating the overflow from the basin is employed.

A further object is to provide a lavatory 20 of a double-basin type embodying a formation which makes provision for adequate self support of the structure both during the drying to which the same is subjected when in the green clay, or plastic, state or condition and during firing, thus not only dispensing with the use of the usual props but 25 also eliminating in large measure losses due to drawing and warping of the structure.

Other objects of the invention will hereinafter be explained or made apparent.

In describing the invention in detail, reference is herein had to the accompanying drawings, in which—

Figure 1 is an under side elevation of 35 the invention as it appears when resting in firing position, and—

Figure 2 is a vertical sectional view of the invention.

Referring to said drawings, 1 indicates 40 the basin, 2 the slab or face, 3 the depending apron or curtain, and 4 the upright back of a lavatory, said parts having forms which are more or less common to lavatories of the general character to which the invention 45 pertains.

A second basin 5, hereinafter termed a catch-basin is formed integral with and depends from the curtain 3, the same being disposed in underlying approximately parallel 50 relation to the basin 1 and the slab 2 and separated from the last named parts by a shallow chamber 6. An outlet opening 7 in the bottom of the catch-basin 5 is preferably located in vertical alinement with the usual 55 drain or waste outlet 8 and is designed for the reception of the end of a waste pipe. An

overflow opening 9 is provided in the upper rear side of the main basin 1, the same providing for the overflow of water directly to the chamber 6.

The catch basin 5 has a central rearwardly extending hollow arm which is designed to serve as a support during the drying and firing processes whereby distortion due to drawing and warping is largely prevented. 65 Said hollow arm is of approximately rectangular form and comprises a relatively narrow flat panel 10 extending rearwardly from the central lowermost portion of the catch basin and located in substantially the same 70 horizontal plane as said portion; substantially vertical side walls 11 rising from the lateral edges of said panel 10 to the walls of said catch-basin; and a vertical panel-like wall 12 rising from the rear end of said 75 panel 10 to the rear side portion or wall of the curtain 3, said wall 12 having its outer face in the same plane with the rear face of the back 4 and the corresponding face of said rear side portion or wall of the curtain. 80

In the drying and firing operations it has been the practice to seat lavatories on their backs and to dispose props in underlying supporting relation to the bowls or basins thereof. However the use of such prop is 85 unsatisfactory because it does not constitute a sufficiently stable support for the heavy overhanging basin to prevent sagging and warping under the influence of the high firing temperatures in which the lavatory and 90 prop—the latter composed of the same material as the lavatory—are naturally subject to considerable shrinkage.

The hollow arm of the present invention constitutes an integral support whereby the 95 lavatory is braced and the catch-basin is adequately supported in both the drying and firing operations, the lavatory being disposed in the furnace in the seated position shown in Fig. 1 in which its back 4 and the 100 panel-like wall 12 of said arm rest flat upon a horizontal surface.

To provide for maintaining the relatively spaced relation between the main basin 1 and the catch basin 5, and also for lending 105 additional support to the bottom portion of the main basin during firing, a plurality of posts 13 is preferably interposed between said basins at suitable points, two such posts, disposed on opposite sides of the waste outlet 110 8, being shown in the drawings. Said posts are introduced in the form of green

rivets, in the molding or shaping operation, being inserted through holes 14 punched therefor in the bottom of the catch-basin. Said posts are made of such length that, 5 with their inner ends firmly seated in underlying relation to the main basin, their outer ends are flush with the under surface of the catch-basin.

10 A marked advantage resulting from the formation of the lavatory with the catch-basin, instead of the usual stuck-on overflow, is that the overflow chamber is of such large capacity that the danger of clogging, or obstruction to free flow of overflow water, is practically eliminated, whereas the small 15 restricted passages of stuck-on overflows are very liable to become clogged.

20 The double-basin construction is produced by the method generally known as single casting, and the back 4 by the method known as double casting. It will be understood, however, that the back may be omitted if desired. In such case the rear wall of the 25 curtain 3 and the wall 12 constitute the seating portions of the structure in the drying and firing periods.

What is claimed is—

1. A lavatory consisting of a one-piece casting comprising a main or upper basin, 30 a horizontal slab surrounding the upper part of said basin, a curtain depending from said slab, and a lower or catch basin supported by said curtain in spaced underlying relation to said main basin, said catch basin having 35 a hollow rearwardly extending arm whereby it is supported during the firing of the lavatory.

2. A lavatory consisting of a one-piece casting comprising a main or upper basin, 40 a horizontal slab surrounding the upper part of said basin, a curtain depending from said slab, and a lower or catch basin supported by said curtain in spaced underlying relation

to said main basin, said catch basin having a hollow rearwardly extending arm 45 whereby it is supported during the firing of the lavatory, said arm comprising a rearwardly extending panel located substantially in the plane of the lowermost portion of said catch basin, and an upright wall joining said panel to the rearmost portion of said curtain and located in the plane of the latter.

3. A lavatory consisting of a one-piece casting comprising a main or upper basin, a horizontal slab surrounding the upper part 55 of said basin, a curtain depending from said slab, and a lower or catch basin supported in spaced underlying relation to said main basin, said catch basin having a supporting arm with a portion thereof occupying a 60 common vertical plane with the rear wall of said curtain and another portion extending horizontally from said vertical portion to the lower part of said catch basin.

4. A lavatory consisting of a one-piece 65 casting comprising a main or upper basin, a horizontal slab surrounding the upper part of said basin, a curtain depending from said slab, a lower or catch basin depending from said curtain in underlying relation to said 70 main basin, and posts interposed between said basins, said catch basin having a hollow arm whereby it is supported during firing of the lavatory, said arm comprising a panel extending rearwardly from said the bottom 75 portion of said catch basin, and an upright wall joining the rear end of said panel to the rear wall of the curtain and occupying the same plane with the latter.

In testimony whereof, I affix my signature 80 in presence of two subscribing witnesses.
